UNITED STATES PATENT OFFICE.

FRIEDRICH GRAFFENBERGER, OF MILWAUKEE, WISCONSIN, ASSIGNOR TO MILWAUKEE LACE PAPER COMPANY, OF MILWAUKEE, WISCONSIN, A CORPORATION OF WISCONSIN.

DESIGN FOR A PLANT COVER.

Application filed September 10, 1928. Serial No. 28,102. Term of patent 14 years.

To all whom it may concern:

Be it known that I, FRIEDRICH GRAFFENBERGER, a citizen of the United States, residing at Milwaukee, in the county of Milwaukee and State of Wisconsin, have invented a new, original, and ornamental Design for Plant Cover, of which the following is a specification, reference being had to the accompanying drawing, forming part thereof.

The figure is a view in perspective of a plant cover, showing my new design.

I claim:

The ornamental design for a plant cover, as shown.

In witness whereof, I hereunto subscribe my name this 7th day of Sept., 1928.

FRIEDRICH GRAFFENBERGER.
